UNITED STATES PATENT OFFICE.

FITZHUGH TOWNSEND, DECEASED, BY JOHN J. TOWNSEND, ADMINISTRATOR, OF NEW YORK, N. Y., ASSIGNOR TO GENERAL RAILWAY SIGNAL COMPANY, A CORPORATION OF NEW YORK.

SYSTEM OF AUTOMATIC SIGNALING FOR ELECTRIC RAILWAYS.

1,159,730.

Specification of Letters Patent.

Patented Nov. 9, 1915.

Application filed April 14, 1910. Serial No. 555,493.

To all whom it may concern:

Be it known that I, JOHN J. TOWNSEND, administrator of the estate of FITZHUGH TOWNSEND, deceased, a citizen of the United States, residing at New York city, county and State of New York, apply for a patent on certain new and useful Improvements in Systems of Automatic Signaling for Electric Railways, invented by said deceased, of which the following is a specification.

The invention relates to a method of controlling automatic block signals on electric railways; the method being especially adapted to roads employing alternating current to operate the cars.

The method of segregating the traffic rails into block sections and of transmitting the power current from one block section to the next may be any one of several well known methods. The drawings in this specification show the bonding coils segregating the blocks, as described in the previous application No. 212,798 of June 16th, 1904.

In the invention he employs a polyphase current as the signaling current; two of the phases of this signaling current traverse simultaneously the traffic rails, and are employed jointly, by means of a relay device responsive to polyphase, but not to single-phase, currents to control the signal. In the arrangement shown in the drawing the signal is maintained in the clear position when both these phases operate jointly. The presence of a car on any block section will short circuit the current of one phase, thus de-energizing the relay, which is not responsive to singlephase, and allow the signal to go to the danger position.

It is possible in the invention to employ one or more of the phases of the polyphase current mentioned above to operate the cars. This particular arrangement is the one shown in the drawings. It will be obvious, to any one skilled in the art, that the cars may, if desired, be operated from any other circuit. The connections of the power circuit then being as described in the application, mentioned above. One of the main advantages, however, of the method described here is that the A. C. transmission line carrying the power current may also supply the current required for signaling purposes, without the necessity of an auxiliary signaling circuit.

One of the features of the invention is, 55 that the power current can never interfere with the control of the signal. The difference of potential between traffic rails for signaling purposes set up at one end of each block, as in many systems of automatic block 60 signaling, is, in this case, of a different phase from that of the power current, and both this and a current of the same phase as the power current are required to operate the relay; either of such currents alone being in- 65 adequate to produce this result.

Figure 1 is a diagram showing the simplest form of the invention, in which a singlephase alternating current supplies both the power current and the signal current. 70 Means are shown for obtaining a two-phase signaling current by splitting the singlephase and obtaining from it a two-phase current, according to any well known method. Fig. 2 shows a system in which the 75 cars are operated by one-phase from a two-phase transmission line; the other phase being employed to impress a difference of potential across the traffic rails at one end of each block. Fig. 3 is a diagram illustrating 80 the application of the system to a three-phase road. In this form of the invention there are two transmission lines, which may be employed respectively to transmit power to the cars, and to furnish current for sig- 85 naling current. The third phase is connected to the track. One of the phases is employed to produce a difference of potential between the traffic rails at one end of each block. This current is transmitted 90 along the two rails of every block section, and at the relay end of the block it combines with currents from the other phases to produce a three-phase system, which is employed to operate a relay; the short-circuit- 95 ing of the current energizing the block, results in giving a singlephase current only to the relay, thus deenergizing it. Fig. 4 is a diagram showing the application of the invention to a three-phase electric railway, 100 using a different relay device from that of Fig. 3.

In Fig. 1, A is the power generator supplying current to the conductor 1 from one collector ring, and having the other collector 105 ring electrically connected to the track rails, by means of the conductor 2 and the bonding coil B. The bonding coils B are connected

at the ends of the block sections across the traffic rails C and D, which are divided up into block sections X, Y, Z. The middle points of said bonding coils are connected together, in order to furnish a path for the power current. The construction of these bonding coils is not a special feature of this invention, for the bonds used may be any of the well-known constructions suitable for the purpose. The transformer E has its primary winding energized from conductor 1 by means of conductor 3. The current from conductor 1 flows through conductor 3, through the winding F to the middle point of the bonding coil B, by means of conductor 4; from there this current returns to the alternator A by means of the traffic rails and conductor 2. The secondary winding G of transformer E is connected across the bonding coil B by means of conductors 5 and 6, thus maintaining a difference of potential across the traffic rails C and D at the end of the block, at which the car leaves it. H is an adjustable inductance for controlling the phase of the current. At the receiving end of the block is a relay I having a stationary polyphase field J and a short circuited rotor K; said rotor carries a contact arm L, which controls the current supplied to the signal solenoid M by the battery N. One phase of said stator coil J is supplied by means of the conductors 7 and 8. The current for this phase is drawn from the trolley wire 1, through the adjustable resistance O, (which may be employed to regulate the phase of the current) through conductor 8, through the stator winding, to conductor 7 to the middle point of the bonding coil B. The current for the other phase is supplied by the difference of potential existing in the absence of a car between the traffic rails C, D, by means of conductors 9 and 10. In this form of the invention the resistance O and the inductance H are so adjusted that a two-phase current is supplied to the stator J. This will normally produce a turning moment upon the rotor K, thus controlling the signal and maintaining it in the clear position. The presence of a car on the block will shunt the current supplied by the transformer E, so that only a single-phase current will be supplied to the stator J, such single-phase current will produce no turning moment. The arm L will fall by gravity against its stop P, thus opening the circuit of the battery N, which will result in a danger signal.

In Fig. 2 the arrangement of the track circuit is the same as in Fig. 1. A is the power generator; one phase of which is supplied to the conductors 1 and 3, which furnish the power current and act in conjunction with the other current phase, carried by the conductors 2 and 4 to furnish

the signaling current. The transformer E in this drawing has its primary F energized from the conductors 2 and 4, by means of conductors 11 and 12. The secondary G energizes the track as in Fig. 1, by means of conductors 5 and 6, passing through the resistance Q, which may be employed to regulate the phases of the current. The relay I is similar in every respect to that shown in Fig. 1 and is connected by conductors 7 and 8 to the secondary R of the transformer S having the primary T, which is energized from phases 1 and 3 by means of conductors 13 and 14. This primary winding passes from conductor 1, through conductor 13, through the winding T through the conductor 14 to the middle point of the bonding coil B and along the traffic rails C, D, to conductor 3 and back to the generator. The other phase of the stator J of the relay I is energized by current furnished by the difference of potential, existing in the absence of a car upon the traffic rails C, D; this current is supplied through the conductors 9 and 10. The operation of this form of the invention is the same as described in connection with Fig. 1.

In Fig. 3 the power generator A is three-phase; one phase is supplied to the track circuit by means of conductor 3, which is connected to the middle point of the bonding coil B. The other two phases are transmitted along the conductors 1 and 2. The transformer E has its primary F energized from conductor 2. The current leaves conductor 2, passes through conductor 12, through the primary winding F, through conductor 11, which is here connected to the middle point of the bonding coil B. The secondary G energizes the track, being connected across the traffic rails at the terminals of the bonding coil B, by means of conductors 5 and 6. Q is an adjustable resistance employed to regulate the phase of the current supplied to the traffic rails by the transformer E. The bonding coil B, at the opposite end of the block, carries a secondary winding U; one terminal of which is connected to the middle point of the bonding coil. The other terminal is connected by means of conductor 15 to a point on the winding of the stator J. V represents an auto transformer energized so that its current leaves conductor 1, flows through conductor 16, through the winding, through the conductor 17 to the middle point of the bonding coil B, along the traffic rails C, D, and from block section to block section, back to the generator to conductor 3. Conductor 18 is adjustably tapped on to some point of the winding of the auto transformer V, so that any desired voltage may be obtained between conductors 17 and 18. The points 19, 20 and 21 will now be fed by three-phase current supplied to them by conductors 18, 125

15 and 22, and this three-phase current will produce a rotary field, which will produce a turning moment of the rotor K, holding the circuit of the battery N closed and 5 resulting in a clear signal, provided no car is on the block. The presence of a car, however, will shunt away from the relay the current supplied by the transformer E, thus de-energizing conductor 15, and converting the 10 field of the stator J from a polyphase to a singlephase field. This will reduce the turning moment to zero and the contact arm L will fall back so as to open the circuit of the battery N, resulting in a danger signal.

15 It will be noted in Figs. 1, 2 and 3 that the connections of the secondaries of transformers E to the track, are reversed in alternate block sections. This reverses the direction of the turning moment of the relay, so 20 that, in the event of the breaking of an insulated joint between block sections, the signal will go to danger. It is deemed sufficient to show one way of accomplishing this result, other methods could obviously be employed if desired. Also the relay device shown is the same in these three diagrams, except for the fact that in Fig. 3 it is three-phase, while it is two-phase in Figs. 1 and 2.

Fig. 4 shows the generator A, the track 30 circuit, and the arrangement of the transformer E and also the transmission lines 1 and 2, arranged as in Fig. 3. In this adaptation of the invention, however, an auto transformer V furnishes a current which 35 combines with the current furnished by the transformer E to produce a three-phase system of currents supplied by the conductors 18, 22 and 15 to the transformers W and X. A diagram of voltages supplied by conductors 18, 22 and 15 would furnish a three-phase delta. The secondaries Y and Z have 40 their terminals reversed, with respect to each other, so that the conductors 23 and 24 which energize the relay, are, at a difference 45 of potential, equal to that existing between conductors 18 and 22; for instance, multiplied by the square root of 3—assuming a 1 to 1 ratio transformation in the transformers W and X. If the secondary winding U of the bonding coil were to be de-energized, the primary windings 25 and 26 50 of the transformers W and X would be connected in series with each other across a single phase; the secondary windings Y, Z being reversed with respect to each other, 55 would then give an electro-motive force be-

tween conductors 23 and 24 equal to zero, thus deenergizing the relay and allowing the arm L to open the circuit of the battery N, resulting in a danger signal. This condition 60 of affairs would be brought about by the presence of a car on a block section, which would shunt the current from the transformer E away from the bonding coil B at the opposite end of the block, reducing the 65 electro-motive force furnished by the winding U to zero.

What is claimed as new is as follows:

1. A system of automatic block signaling comprising a source of polyphase current, a trackway, means for segregating the trackway into block sections, means for impressing one phase from the polyphase source upon the trackway, a relay normally actuated by all of the phases from the polyphase source, one of the several phases normally actuating the relay being transmitted through the trackway, and a car actuated by one phase from said source. 70
2. A system of automatic block signaling comprising a trackway, a source of alternating currents, means for segregating the trackway into block sections, means for impressing one phase from said source upon the trackway, a relay normally actuated by a plurality of phases from said source, one of the phases normally actuating the relay being transmitted through the trackway, and a car actuated by one phase from said source. 75
3. A system of automatic block signaling comprising a trackway, a source of alternating currents, means for segregating the trackway into block sections, means for impressing a phase from said source upon the trackway, a relay normally actuated by a plurality of phases derived from said source, one of the phases normally actuating the relay being transmitted through the trackway, and a car actuated by a phase from said 80 source, at least two of the phases actuating the relay differing from the phase actuating the car. 90

In testimony whereof, I affix my signature, in the presence of two witnesses.

JOHN J. TOWNSEND,
Administrator of estate of Fitzhugh Townsend, deceased.
